US00D463144S

(12) **United States Design Patent** (10) Patent No.: **US D463,144 S**
 Pennington et al. (45) Date of Patent: ** Sep. 24, 2002

(54) **CHAIR**

(75) Inventors: **Mark Rundle Pennington**, Wellington (NZ); **Jon Leonard Fifield**, Wellington (NZ); **Kent Wallace Parker**, Wellington (NZ)

(73) Assignee: **Formway Furniture Limited**, Wellington (NZ)

(**) Term: **14 Years**

(21) Appl. No.: **29/143,322**

(22) Filed: **Jun. 12, 2001**

Related U.S. Application Data

(63) Continuation-in-part of application No. 29/130,410, filed on Sep. 28, 2000, now Pat. No. Des. 446,397.

Foreign Application Priority Data

Apr. 26, 2001 (NZ) 401711

(51) LOC (7) Cl. **06-01**

(52) U.S. Cl. **D6/366**

(58) Field of Search D6/334, 364, 365, D6/366, 367, 500, 501, 502; 297/411.2
